JOSEPH G. SCHOTTHOEFER, OF PEORIA, ILLINOIS.

PUMPING MECHANISM.

Application filed April 7, 1927. Serial No. 181,695.

A primary purpose of this invention is to provide a pumping mechanism of a nature such that it will deliver liquid to a place of use for power, lubricating or other purposes, 5 under variable pressures with a most economical expenditure of the energy required in the operation of the pump.

In the accomplishment of this primary purpose the invention contemplates the provision of a pump comprising a plurality of related pumping units and a control means common to said pumping units and operative at the will of the operator to vary the quantity or volume of liquid discharged by the 15 pump.

The invention further contemplates as important purposes thereof, the provision of means whereby the aforesaid primary purpose may be accomplished by simple and 20 effective means and more particularly by controlling means and liquid-forcing elements so correlated that many different volumes or quantities of liquids may be selectively delivered under pressure from the 25 pump without complicating the construction of the pump or resorting to means of delicate or expensive construction.

To these several ends, the invention consists in certain novel combinations and 30 correlation of elements substantially as herein-after described and particularly set forth in the appended claims.

While I recognize that means illustrated in carrying this invention into practice are applicable in principle to pumps of various 35 kinds or types and while I contemplate the application of such means to pumps of any kind or type to which they are applicable, I have elected to illustrate and shall herein- 40 after describe the application of the invention to pumps of the rotary type, and especially to that kind of rotary pumps which include rotary impellers and appropriate intermeshing teeth for imparting rotary movement from one impeller or its shaft to another impeller or its shaft, without, however, intending thereby to restrict the invention in all of its respects to rotary pumps. 45 Moreover, I am aware that details of the particular means illustrated in the drawings and

described in this specification may be substantially varied without departing from the spirit of the invention as defined by appended claims. In short, I would have it understood that the drawings illustrate and the 55 description sets forth preferred embodiments having many advantages in relation to the purposes underlying this invention.

In said drawings, wherein like characters of reference denote corresponding parts in 60 all the figures:—

Fig. 1 is a longitudinal section and exemplifies the invention as applied to a rotary pump the peripheries of whose impellers are provided with intermeshing teeth, this figure also exemplifying a form of the invention in which the controlling means are arranged rearward of the impellers, the figure showing a controlling member and the mouth of a corresponding by-pass located between 70 the impellers and the corresponding check valve which controls the outlet port from the corresponding chamber.

Fig. 2 is a similar view on the line 2—2 of Fig. 7, but exemplifies a form of the invention in which the control valves are arranged in advance of the corresponding impellers and are operative by the controlling means to cut off the supply of the liquid to the 75 chambers in which said impellers operate. 80

Fig. 3 is a vertical section on the line 3—3 of either Fig. 1 or Fig. 2.

Fig. 4 is a vertical section on the line 4—4 of Fig. 5, (but with parts of the casing broken off and with certain parts omitted) this figure being intended to illustrate a form of the invention in which the rotary impellers are connected for simultaneous movement in opposite directions by intermeshing gears mounted upon the ends of the impeller shafts, 85 instead of by intermeshing teeth formed on the peripheries of the impellers themselves. 90

Fig. 5 is a vertical section on the line 5—5 of Fig. 4.

Fig. 6 (Sheet 2) is a horizontal section on 95 the line 6—6 of Fig. 1.

Fig. 7 is an end elevation of the construction shown in Fig. 1.

Fig. 8 is a side elevation of the embodiment illustrated in Fig. 1.

Fig. 9 is a detail view of one of the inside plates which separate pumping units from each other.

Fig. 10 is a detail view of the indicator and the cams forming a part of the controlling means applicable to the form of the invention in which the supply to the pump is controlled at a place in advance of the rotors. (See Fig. 2.)

10 Fig. 11 is a detail view of the cams applicable to the form of the invention in which the controlling means is between the impellers and the check valve. (See Fig. 1.)

The pump forming the subject of this invention essentially includes a plurality of separate pumping units each having an inlet port, an outlet port and a liquid-forcing means operating between said ports. These units may be of any suitable construction ap-

15 propriate to the purpose to which the pump is to be applied. While there may be any suitable number of units, more than one, three of said units have been illustrated since this number will be appropriate in many in-

20 stances. These units include chambers designated respectively A, A' and A². The chambers are preferably arranged in a casing constructed of a front member A³, a rear member A⁴, and a suitable number of internal 25 plates A⁵. These members and plates are rigidly secured together—as by bolts 15 and nuts 16—in proper relations to provide the said chambers A, A', and A². In the embodiment of the invention in which provision is

30 made for by-passing the part of the liquid delivered to the pump in excess of that to be delivered at the place of use, the members A³, A⁴ and plates A⁵ are, as shown best in Figs. 1 and 6, also formed to provide an inlet channel B, an outlet channel B', and a by-pass channel B², and also ports b connecting the inlet channel B with the chambers, respectively, ports b' connecting the respective chambers with the outlet channel B' and

35 ports b² leading to the respective by-pass channels B². The by-pass channel B², shown in said figures, is arranged rearward of the liquid-forcing means of the pump, in which event the by-pass ports b² will tap the outlet 40 channels b', but said by-pass channel may be otherwise arranged if preferred; or, as shown in Fig. 2, the by-pass channel in the pump casing may be eliminated entirely by cutting off the flow of liquid in the inlet port b, prior

45 to its admission to the corresponding chamber. The arrangement shown in Fig. 1 may be preferred particularly when oil is the liquid pumped and the liquid-forcing means are of a kind requiring lubrication, since the 50 said arrangement will assure continuous lubrication thereof while the pump is in operation.

The illustrated liquid-forcing means is composed of rotary impellers C and C' opera-

tive in the several chambers. As is customary, these impellers have their peripheral surfaces formed to provide pockets which receive the liquid drawn through the inlet ports b and discharge said liquid into the outlet ports b'. These impellers, as also is customary, are driven simultaneously in opposite directions through appropriate connections. As shown in Figs. 1 and 2, their peripheries may be formed with teeth 20 of which those of one impeller intermesh with those of the other impeller, the spaces between the bases of the teeth providing pockets 21 for the liquid. In another form, illustrated in Figs. 4 and 5, the gears, marked 20^a and 20^b, instead of being formed on the peripheral surfaces of the impellers, marked C^a and C^b, are mounted on the impeller shafts, and the peripheral surfaces of the impellers instead of having intermeshing teeth for transmitting rotary movement from one to another are each provided with two teeth c, and with two openings c', arranged as shown. The spaces between the teeth c in this form provide elongated pockets for the liquid pumped. In both forms the pockets are defined by the sides of the teeth, the peripheral surfaces of the impellers and those parts of the walls of the chambers with which the outer ends of the teeth contact in the operation of the impellers. It may be here mentioned that while the several passages and ports for the flow of the liquid within the pump have not been shown in Figs. 4 and 5, yet in the practical embodiment of this form, these passages and ports will be included, the casing being preferably of substantially the construction shown in relation to the form in which the impellers are geared together through the medium of intermeshing teeth formed on their peripheries, except that when the gears are mounted on the shafts the casing will preferably include, as shown, provision for the enclosure of said gears.

It will be understood that there is a pair of impeller sections in each chamber A, A' and A². Because of the resultant simplicity of construction, it is preferred that each impeller, instead of being composed of independently rotative sections mounted in the respective chambers, be of a unitary construction; that is that its sections and shafts be substantially integral. This preferred construction, therefore, has been illustrated. Upon reference to Fig. 3 it will be noticed that each impeller C, C' has its ends formed to provide shafts 24 which extend through openings formed in the side members A³ and A⁴ of the casing. Adjacent these shafts, each impeller has shoulders 25 which bear against the inner surfaces of said casing members surrounding the shaft openings, and intermediate its said shoulders each impeller has recesses 26 to receive the portions of the divi-

sion plates A^5 bounding the openings 27, 27' (see Fig. 9) formed in each division plate, these openings being provided to permit the unitary shafts and impeller sections to extend therethrough. One of the shafts 24 is extended outward for the attachment thereto of a prime mover, not shown, of any suitable kind. A stuffing box including members 28 and 28' is preferably mounted on this extended shaft end. The end members A^3 and

A^4 are provided with flanges 29 which are concentric with the shafts 24 and are spaced therefrom, and friction-reducing bearings, as rollers 30, are interposed between said shafts 15 and flanges. A casing plate A^{30} closes the outer side of the member A^3 and a casing plate A^{31} , together with the member 28 of the stuffing box, closes the outer side of the member A^4 .

20 The impellers C^a and C^b and their shafts similarly are preferably of unitary construction and said impellers have shoulders and recesses as described in relation to the other form. Each internal division plate A^5 in this embodiment also is like the corresponding plates of the other embodiment of the invention, but there is one additional plate and the shoulders of one end of the impellers bear against this additional plate. The side member, marked A^{40} , (see Fig. 5) corresponding to the member A^4 in the other form, is spaced from this additional division plate to provide between them a chamber to receive the gears 20^a and 20^b. This end plate has outwardly projecting flanges 29^a forming rings concentric with the shafts 24 to provide for friction-reducing bearings, as rollers (30') similar to those marked 30 in the other form, and one of these rings is closed at its outer 35 end by the member 28^a of a stuffing box while the other rings are closed at their outer ends by plates 30^a. Thus in this particular exemplification, the gears as well as the impellers are encased. The enclosure of the gears is, 40 however, not essential.

45 Each of the division plates A^5 is divided, as along the line a , Fig. 9, for convenience in assembling the parts when the impellers and their shafts are of integral formation.

50 For reasons which will hereinafter be explained, the chambers A , A' , and A^2 are of relatively different capacities and the sections of the impellers within said chambers are of correspondingly different sizes; that 55 is, longitudinally of the impellers, the sections in the chamber A are the shortest, the sections in the chamber A^2 are the longest and the sections in the chamber A' are of a length intermediate the others.

60 Individually operable check valves D are operatively related to each outlet port b' and to the channel B' common to said ports and individually operative control valves E arranged in advance of said check valves. In 65 practice, the discharge end of the channel

B' is connected to a pipe leading to the place to which the pumped fluid is to be conducted for use, as in applying power to move an object, for example. The by-pass channel B^2 is 70 preferably connected with the source of supply of the liquid, and in the embodiment shown in Figs. 1 and 6 the control valves E are operatively related to the by-pass ports b^2 connecting the outlet ports b' with the by-pass channels B^2 . 75

The illustrated check valves D are provided with springs whose tension will hold them severally closed against their seats except when overcome by the pressure of the liquid being pumped through the corresponding outlet ports or channels b' . The liquid will exert such pressure in the operation of that embodiment of the invention employing a by-pass, when the corresponding by-pass port b^2 is closed. When, however, any one or more of 85 such by-pass ports b^2 is opened by its valve E , the pressure of the liquid, if any pressure is exerted against the corresponding check valve or valves D , will not cause said check valves to open, even when the by-pass ports 90 are between the impellers and the outlet channel B' , since the liquid will then be discharged into the by-pass channel B^2 from which it will be returned to its source, or be otherwise disposed of. 95

In that embodiment of the invention in which provision is made for the cutting off of the supply of liquid to any of the chambers through the medium of valves, as E , controlling the inlet channels, the check valves D , 100 of course, will be opened only when the corresponding control valves E are open, since at this time only will the pressure of the liquid against the check valves be sufficient to open them. 105

In short, in the one illustrated embodiment, the closing of any control valve causes the flow of liquid to the corresponding chamber to be cut off and in the other illustrated embodiment the opening of any one of the control valves causes the flow of liquid from the corresponding chamber to be cut off, and in either embodiment this cutting off of the flow of liquid, being in advance of the check valves, will correspondingly cut down the 110 supply to the outlet channel B' . 115

It will be apparent that the springs d become operative to close the corresponding check valves when the pressure of the liquid in the corresponding chamber drops below 120 that predetermined for the opening of said valves, and also that the closing of any check valve cuts off from the corresponding chamber any back pressure created by the resistance of the load to the pressure exerted thereagainst by liquid being pumped from one or more of the chambers whose by-pass ports are closed and whose check valves are open. Hence, it will be noted that the correlation of 125 impellers, check valves, inlet and outlet ports 130

and channels, and also the by-pass when used, is such that the work of the impellers is confined to the pumping of only the quantity or volume of liquid required for the work to be performed by said liquid at the corresponding moment and that it performs its work without any interference due to back pressure even when it is delivering the liquid from one of the chambers only and that the one of smallest capacity.

Thus, it will be apparent that the power applied to operate the pumps will vary in accordance with the variations in the quantity or volume of liquid delivered for use, without necessitating any variation in the speed of the impellers. In this relation, it should be particularly noticed that the by-passing of that part of the liquid delivered to the pump which is in excess of that to be delivered at the place of use occurs at a place or places at which the liquid is not under pressure, whereas it has heretofore been the practice, with those pumps employed in systems in which variable conditions as to pressure, resistance etc. have been met by by-passing the part of the liquid in excess of that required, to so bypass the liquid at a place or places in the system at which the liquid is under pressure and since in such systems the pump is operating at all times at the same speed, it accordingly has been called upon to pump the same quantity or volume of liquid and requires the same amount of energy to operate it under all conditions of use—that is, whether all or whether only a part of the volume or quantity of liquid pumped is actually delivered at the place of use. In the instant invention, however, the energy supplied by the prime mover is lessened in accordance with the number of pumping units whose by-passes are open and the saving of power in the operation of the pump, therefore, will be apparent. This presupposes that the resistance to the pressure of the liquid remains the same. If, however, the pump is applied to a work which the resistance to the pressure of the liquid pumped is variable, the power applied to the pump by the prime mover may remain constant, the speed of rotation of the impellers similarly may remain constant, while the quantity or volume of liquid delivered may vary in accordance with the varying resistances, it being apparent that when the resistance is increased and the volume of liquid correspondingly reduced, the pressure of the liquid will be increased to meet the increased resistance, if the power of the prime mover applied to the pump remains the same.

While reference has herein been made to a pump whose liquid-forcing means, herein exemplified by rotary impellers, have been assumed to operate at a constant speed under all conditions, and while the prime mover has also been referred to as being one operating to deliver variable power to the pumping

means, it is apparent that the mechanism may be employed, with an appropriate prime mover and connections, under conditions in which it is advisable to vary the speed of the pumping means. By thus varying the speed of the pumping means, the capacity of each section of the pump, and of the pump as a whole, may be correspondingly varied, and this variation will result in a corresponding variation in the pressure applied by the pump, since it correspondingly varies the speed of flow of the liquid and hence the volume delivered within a given time.

This invention contemplates as one of its most important features the provision of a control means operatively related to the pumping means and their chambers, and to the ports and channels provided for the flow of the liquid, and which control means is operative to effect a selective control of the flow of the liquid, the said control means being further of such nature that it will be capable of co-operating with the pumping means, chambers, ports and channels to bring about a change in the volume or quantity of liquid delivered by the pump, at the will of the operative, without necessitating any change in the speed of operation of this pump. This control means operates the valves E and in the illustrated embodiments of the invention is additionally characterized in that it is operative to control said valves both individually and in different combinations thereof, effecting corresponding changes in the delivering of the liquid. Reference has hereinbefore been made to the fact that the chambers A, A', and A² may be of relatively different capacities and that this is true also of the liquid-forcing means therein. Therefore, it will be apparent that when the liquid delivered is that which passes through the smallest chamber (A) only, the quantity or volume thereof will be less than that which will be delivered when it passes through the second chamber (A²) and still less than that which passes through the next chamber. The difference in the capacities of the chambers A, A' and A² accordingly contributes to the production of changes of successively increasing or successively decreasing nature. Moreover, by providing for the control of the liquid with respect to different combinations of the chambers, the number of the changes which may be effected is correspondingly increased. It will be noted that the changes thus far referred to are accomplishable without any change in the speed of the liquid-forcing means and without any difference in the extent of the opening of a control valve. A wider range of changes, however, may be effected without any change in the construction of the pump, by operating its liquid-forcing means at variable speeds and provision for this, of course, can be made by the employment of well known prime mov-

ers and connections to the pump. In a pump having such provision, the volume of the liquid delivered at the place of use in a given time from any one of the chambers, or 5 from any combination of more than one thereof may be changed by correspondingly changing the speed of the liquid-forcing means. Thus concluding this preliminary summary of the results obtainable from a 10 correlation of parts including a control means of the nature contemplated by me, I will now describe embodiments of the control means suitable for the purposes, the said embodiments being alike in principle 15 but differing in details to adapt them to the forms of the invention exemplified by Fig. 1 and Fig. 2, respectively.

As already stated, this means may be conveniently applied to control the valves E. 20 These valves, therefore, are of a nature suitable for control by said means, being here shown as having members E' extending to places where they, respectively, may be operated upon by cams F, G and H, (Fig. 10) or 25 F', G' and H', (Fig. 11), which cams operate to move the valves E in opposition to coiled springs E². In each of these exemplifications, the springs tend to open the valves and the cams to close them.

30 In each, the cams (F, G and H in the one form and F', G' and H' in the other form) are mounted upon a common shaft, which being identical in both embodiments is marked I throughout the drawings. In each 35 embodiment, moreover, the cams have high and low parts so correlated that the control of the valves E individually and in predetermined combinations hereinbefore referred to may be brought about at the will of the operative, but in the embodiment illustrated in 40 Figs. 2 and 7, the high parts of the cams (Fig. 10) are arranged to close the valves E corresponding to chambers which are to be cut out of operation by said closing, while in the 45 embodiment in which the valves E are arranged to control by-pass ports between the chambers and check valves, the cams (Fig. 11) are arranged to close the valves E corresponding to chambers which are to be and 50 which become operative by said closing.

Thus referring first to the embodiment in which the valves E are arranged in advance of the rotors, and particularly to Figs. 2, 7 and 10, it will be noticed that the cam F has peripheral openings 30, 31 and 32 and high parts 36, 39 and 41; the cam G has peripheral openings 33 and high parts 37 and 40; and the cam H has a peripheral opening 35 and a high part 38. The cam F is arranged to operate the valve E corresponding to the smallest chamber (A); the cam G is arranged to operate the valve E corresponding to the intermediate chamber (A^2); and the cam H is arranged to operate the valve E corresponding to the largest chamber (A^2). A

dial or indicating plate J is also mounted upon the shaft I. The plate J and cams are keyed upon the shaft I in relative position such that when all of the valves E are closed the dial will indicate the same by the position of its zero mark and the high parts 36, 37 and 38 of the respective cams will be in contact with the ends of the valve members E' respectively. If now, it is desired to utilize the flow of liquid from chamber A alone, the shaft I is turned by any appropriate means until the indicating mark "1" on the dial J will be in the position which indicates that the shaft I has been turned sufficiently to carry the high part 36 of cam F out of engagement with and the opening 30 into registration with its corresponding member E'. The spring which operates the valve E corresponding to chamber A then becomes effective to open said valve. The high parts 37 and 38 of the cams G and H at this time remain in engagement with the valve members corresponding to chambers A' and A², since the movement of the cams has not been sufficient to disengage them from said members. A further movement of the shaft I, to the position indicated by mark "2" on the dial, will carry the high part 39 of cam F into engagement with the corresponding valve member, thus closing the valve E corresponding to chamber A, and at the same time will carry the high part 37 of cam G out of engagement with the valve member E' corresponding to chamber A' and the opening 33 of said cam into registration with said valve member, whereupon the valve E corresponding to said chamber A' will be opened. A still further movement of the shaft I, to the position indicated by the mark "3" on the dial, will disengage the high part 38 of cam H from the member E' of the valve corresponding to chamber A² and will place the recess or low part 35 of said cam into registration with said valve member, whereupon the corresponding valve E will be opened by its spring. This movement of the shaft has brought the high part 40 of cam G into engagement with the member E' of the valve corresponding to chamber A', so that said valve is closed thereby, but has not been sufficient to disengage the high part of 39 of cam F from the corresponding valve member and hence the valve E corresponding to chamber A remains closed. Thus it will be seen that the flow of liquid from the chambers to the place at which the liquid is to be used may be so controlled that the liquid delivered at said place may be that from any one of the chambers, and since these chambers vary in their capacities the volume of the liquid delivered at a given time will be correspondingly varied. It may be here mentioned that the relative variations in the capacities of the chambers preferably is such that the volume of liquid delivered from chamber A' and

from chamber A' in a given time will be respectively one and one-half and twice that delivered from chamber A. These are practical proportions which, however, may be varied if preferred. If now it is desired to deliver a larger volume than is obtainable from chamber A' alone, a still further movement of shaft I to the position indicated by dial number "4" will carry the high part 39 of cam F out of engagement with the member E' of the valve E corresponding to chamber A and the recess or low part 31 of said cam into registration with said valve member but this movement will not be sufficient to disengage the high part 40 of cam G from the corresponding valve member, or to re-engage the high part 38 of cam H with its corresponding valve member. Hence, the valves corresponding to chambers A and A' will be opened while the valve corresponding to chamber A' will remain closed. The next step in the increasing of the volume delivered at the place of use will be the closing of the valve corresponding to chamber A and the opening of the valve corresponding to chamber A', without, however, closing the valve corresponding to chamber A'. This is accomplished by turning the shaft I until the indicating mark "5" is in indicating position. This movement carries the high part 41 of cam F into engagement with the member of the valve corresponding to chamber A, thus closing said valve, and at the same time carries the low part 34 of cam G into registration with the member of the valve E corresponding to chamber A', thus permitting the spring E' of the latter valve to open the same; but since this movement is insufficient to bring the high part 38 of cam H into engagement with the member E' of the valve E corresponding to chamber A', the latter valve remains open. The last step in the control of the volume delivered at the place of use, in this embodiment of the invention, is the turning of the shaft to the position in which the dial indicator 6 is in indicating position. This movement of the shaft causes the recess or lower part 32 of cam F to register with the member D' of the valve E corresponding to chamber A' without engaging high parts of the other cams with their respective valve members. Hence, the volume of the liquid now delivered will be the aggregate of that flowing from all three chambers. A further turn of the shaft I to the position at which the zero mark on the dial is in indicating position will cause the high parts of all the cams to engage their respective valve members E' thus closing all valves E and cutting off the flow of liquid entirely.

Referring now to the embodiment in which the valves E are arranged between the rotors and the check valves D are control by-pass ports b², and particularly to Figs. 1, 8 and 11, it will be noticed that the high parts of the cams (marked F', G' and H' in this embodiment) are disposed in substantially the same position as the low parts of the corresponding cams F, G and H, and that this is true also with relation to the low parts of said cams F', G' and H', the said low parts being in substantially the same position as the high parts of the cams F, G and H. In the operation, therefore, of this particular embodiment, when the indicator, (which being identical in both forms is marked J throughout the drawings) is turned to the zero position, low parts 30', 35' and 39' of the cams F', G' and H' will be presented to the respective valves E which valves at this time will be held in open position by their springs E², thereby causing all liquid from the several chambers to be by-passed. When the shaft is turned to the position indicated by "1" on the indicator J, the corresponding valve E will be closed by the high part 31' of cam F' thereby rendering chamber A effective; when the shaft is turned further, as to the position indicated by "2" on the indicator J, the high part 31' of cam F' will be disengaged from the corresponding valve E which valve will thereupon be opened and the high part 36' of cam G' will be engaged with the valve E controlled by said cam, the said valve being thereby closed, the opening of the valve controlled by cam F' thus rendering chamber A ineffective and chamber A' effective; a still further turning of the shaft I, to the position indicated by "3" on the indicator J will disengage the high part 36' of cam G' from its valve E and will engage the high part 40' of the cam H' with the valve E controlling chamber A². At this time the low part 32' of cam F' remains presented toward its valve E and hence said valve, which controls the by-pass port corresponding to chamber A, remains in open position. Accordingly, it will be seen that when the shaft I has been turned to the position indicated by "3" in indicator J, chambers A and A' will be non-effective since the corresponding by-pass ports b² will be open and hence liquid pumped from said chambers will flow into the by-pass B² instead of into the conduit or channel B', while chamber A² will be effective, since the corresponding by-pass port b² will be closed. Turning of shaft I to the position indicated by "4" on indicator J will engage the high part 33' of cam F' with the corresponding valve E without disengaging the low part 37' of cam G' from its valve and without disengaging the high part 40' of cam H' from its valve. It follows, therefore, that in this position of its shaft and cams, the valves E controlling the by-pass ports b² corresponding to chambers A and A² will be closed while the valve E controlling the port b² corresponding to chamber A' will remain open; hence chambers A and A² will be non-effective. A still further rotation of the shaft 130

to the position indicated by "5" on the indicator J will disengage the high part 38' of cam F' from the corresponding valve E and present the low part 34' of said cam to said valve, and at the same time will engage the high part 38' of cam G' with the corresponding valve but will not disengage the high part 40' of cam H' from its corresponding valve. Hence, in this position of the parts the valve 10 controlling the by-pass port corresponding to chamber A will be open and said chamber will be ineffective to supply liquid to the conduit or channel B', while the valves controlling the by-pass ports corresponding to chambers A' 15 and A² will be closed and said chambers thereby will be effective to supply liquid to said conduit or channel. A still further rotation of the shaft, to the position indicated by "6" on the indicator J will engage the high 20 part 30' of cam F' with its corresponding valve E without disengaging the high parts 38' and 40' of the cams G' and H' from their respective valves E, the result being that all chambers A, A' and A² will be effective to 25 supply liquid under pressure to the channel or conduit B' since all by-pass ports b² are closed by their respective valves. Finally, the next movement given the shaft I, to the 30 position indicated by "0" in the indicator J, disengages the high parts of all cams from the valves respectively and presents the low parts 30', 35' and 39' of said cams to the respective valves, whereupon the springs E² of the valves become effective on the valves to 35 open all the by-pass ports, thereby rendering all chambers non-effective to supply liquid to the conduit or channel B'.

It will be understood that the type or kind of pump—that is, whether it be of rotary or 40 other nature—the number and the relative capacities of the pumping units, the number of the selectable combinations of the pumping units and, in short, the details herein illustrated are matters of choice and may be substantially varied within the scope of appended claims.

Having thus described the invention and set forth in detail what I regard to be the most practicable embodiment, what I claim 50 as my invention and desire to secure by Letters Patent, is:—

1. A pumping mechanism comprising a plurality of pumping units, each having a check valve and each also having a control valve arranged in advance of its check valve, and a control means common to said control valves and including a plurality of members operatively related to said valves respectively and operative to control the 60 same selectively.

2. A pumping mechanism comprising a plurality of pumping units each having a control valve and each also having a check valve arranged rearward of the control 65 valve, a liquid supply channel having ports

for the inlet of the liquid to said units, an outlet channel having ports controlled by the check valves, and a by-pass channel having ports controlled by the control valves, and a control means including a plurality of members operatively related to said control valves respectively and operative to control the same selectively. 70

3. A pump comprising a casing having a plurality of chambers and provided with an inlet channel and an outlet channel and with ports through which each channel has separate communication with the corresponding chamber, the casing also having by-pass ports operatively related to the chambers, respectively; valves to open and close the by-pass ports, respectively; and a means common to said valves and including members respectively operative with relation to the valves to cause the same to be opened and closed selectively. 75 80 85

4. A pump comprising a plurality of pumping units and provided with an inlet channel and an outlet channel and with ports through which each channel has separate communication with the units, the pump also having by-pass ports in advance of the outlet channel; check valves operatively related to the respective units and to the outlet channel; by-pass valves for the respective by-pass ports; and a means common to the by-pass valves and including members respectively operative with relation to said valves and operative to control the same selectively. 90 95

5. A pump comprising a casing having a plurality of chambers and provided with an inlet channel and an outlet channel and with ports through which each channel has separate communication with the chambers, the casing also having by-pass ports in advance of the outlet channel, check valves operatively related to the respective chambers and controlling communication thereof with the outlet channel, by-pass valves for the respective by-pass ports, and a means common to the by-pass valves and including members respectively operative with relation to said valves and operative to control the same selectively. 100 105 110

6. A pump comprising a plurality of chambers, rotary impellers therein, check valves at the delivery sides of the chambers and a plurality of control valves in operative relation with the chambers and controlling the flow of liquid in advance of the check valves, and a control means common to said control valves and including members operatively related to the valves respectively. 115 120 125

7. A pump comprising a casing having a member therein formed of sections which jointly form a wall dividing the casing into a plurality of chambers, and a pair of rotary impellers each having a substantially integral body part and shaft, with its body part extending through the division member to pro- 130

- vide working sections thereof in both chambers and formed with a circumstantial groove into which the portions of the division member are seated.
5. 8: A pump comprising a casing, a pair of rotary impellers mounted in the casing and each having a body part provided with a peripheral groove separating it into separate working sections, and means co-operating 10 with said sections to divide the casing into a plurality of separate pumping units, in parallel, including separate chambers which receive corresponding sections of both impellers, said casing-dividing means formed of sections 15 having openings the boundaries of which are seated in said grooves of the impellers, respectively.
9. A pump comprising a casing, a pair of rotary impellers mounted in the casing and 20 each having a body part provided with a peripheral groove, and division plates to divide the casing into a plurality of chambers of different capacities each of which chambers receives corresponding sections of both impellers, each of said plates formed of sections 25 having openings the boundaries of which are seated in corresponding parts of the grooves of the impellers, respectively.
10. A pump comprising a plurality of 30 pumping units, a plurality of control valves in operative relation with the units, respectively, a control means for the valves including members operatively related to the respective valves, and a means having elements 35 which partake of movement imparted to said members and which respectively indicate the positions of said members with relation to the valves.
11. A pump comprising a plurality of 40 pumping units, a plurality of control valves in operative relation with the units, respectively, a control means for the valves including cams whose high and low parts are correlated with each other and with the valves to 45 control the valves selectively, and a means movable with said cams and having elements related to the high and low parts thereof to indicate the positions of said parts with relation to the valves.
- 50 12. A pump comprising a plurality of pumping units, a plurality of control valves in operative relation with the units, respectively, a control means for the valves including a rotative shaft and cams mounted on the shaft and whose high and low parts are correlated with each other and with the valves to control the valves selectively and a dial also mounted on said shaft and movable therewith and with said cams and having 55 elements related to the high and low parts of
- said cams to indicate the positions of said parts with relation to the respective valves.
13. A rotary pump comprising a plurality of pumping units each having an inlet port, an outlet port and rotary pumping means operating between said ports, each unit also having a check valve controlling the outlet port and a control valve arranged in advance of the check valve and operative to control the pressure exerted by the pumping means 65 against said check valve, in combination with a means to open the control valves, said means including members settable by the operation of said means to different selecting positions with respect to each other and to 70 said valves and operative to open the valves respectively in accordance with the position into which said means have been set.
14. A pumping mechanism comprising a plurality of pumping units each having a tensioned check valve at the delivery side thereof and a tensioned control valve in advance of the corresponding check valve and a control means common to said control valves and including a plurality of members operatively 80 related to said control valves respectively and co-operating with the tensioning means of the control valves to operate the latter selectively.
15. A pumping mechanism comprising a 85 plurality of pumping units, each having a tensioned check valve at its delivery side and each also having a control valve in advance of the check valve, tensioning springs to move the respective control valves in one direction, 90 a rotative shaft having cams, respectively, to operate the control valves in opposition to the springs of the latter, the cams having high and low parts correlated with each other and with the control valves to operate the 100 latter selectively in accordance with the positions to which they have been set by rotative movement imparted to the shaft, and a member also mounted on said shaft and having elements correlated with the high and low 105 parts of the cams to indicate the positions of the latter with relation to the control valves.
16. A rotary pump including a casing having a partition wall dividing it into a plurality of separate chambers, said chambers having separate supply ports and separate discharge ports, selectively controllable control valves for said chambers, respectively, and rotary impellers having co-acting impeller sections arranged in each of said chambers, and co-operating with said wall, ports and valves to provide a plurality of rotary pumping units, in parallel.

In testimony whereof I affix my signature.
JOSEPH G. SCHOTTHOEFER.
